Primary Examiner — Sheryl Lane*Assistant Examiner* — Ieisha N Price(74) *Attorney, Agent, or Firm* — Iandiorio Teska & Coleman, LLP(57) **CLAIM**

I claim the ornamental design for the shelf support bolt, as shown and described.

DESCRIPTION

FIG. 1 is a front perspective view of a shelf support bolt in accordance with the present invention;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.

The broken lines in the drawings depict portions of the shelf support bolt and form no part of the claimed design.
